TRACK ROLLER GUARD

Ronald J. Fanslow, Schamburg, Donald E. Wilkinson,
Melrose Park, and Jack M. Deli, Wheaton, Ill., assign-
ors to International Harvester Company, Chicago, Ill.,
a corporation of Delaware

Filed Sept. 6, 1966, Ser. No. 3,736

Term of patent 14 years

(Cl. D14—3)

FIG. 1.

FIGURE 1 is a face view of a track roller guard embodying our new design, and appearing in a right side elevational view of, and mounted on a track frame of, a tractor;

FIGURE 2 is a face view similar to FIGURE 1, but being fragmented in length and drawn to enlarged scale;

FIGURE 3 is a plan view as seen from the top of FIGURE 2, and taken along the section lines III—III thereof;

FIGURE 4 is a side view as seen from the left of FIGURE 2;

FIGURE 5 is a side view as seen from the right of FIGURE 2 and as taken along the section lines V—V; and

FIGURE 6 is a plan view as seen from the top of FIGURE 2, drawn to enlarged scale and taken along the section lines VI—VI.

The dominant features of the design reside in the portions shown in full lines, and the tractor shown fragmentarily in broken lines in FIGURE 1 is intended for illustrative purposes only.

We claim:

The ornamental design for a track roller guard, as shown and described.
